WATER SOFTENER

Howard R. Moon, Fort Atkinson, Wis., assignor to Borerud Manufacturing Company, Inc., Deerfield, Wis., a corporation of Wisconsin

Filed Apr. 12, 1965, Ser. No. 84,746

Term of patent 3½ years

(Cl. D91—1)

FIG. 3

FIG. 1 is a right front perspective view of a water softener showing my new design;

FIG. 2 is a right rear perspective view thereof;

FIG. 3 is a right elevation thereof; and

FIG. 4 is a front elevation thereof.

The dominant features of my design reside in the portions shown in full lines.

I claim:

The ornamental design for a water softener, substantially as shown and described.
